J. K. BOSWELL.

Fruit Drier.

No. 64,065.

Patented April 23, 1867.

UNITED STATES PATENT OFFICE.

JOHN K. BOSWELL, OF RICHMOND, INDIANA.

IMPROVEMENT IN FRUIT-DRIERS.

Specification forming part of Letters Patent No. 64,065, dated April 23, 1867; antedated March 16, 1867.

To all whom it may concern:

Be it known that I, JOHN K. BOSWELL, of the city of Richmond, county of Wayne, and State of Indiana, have invented a new and useful Improvement in Dry-Houses, to be known as a "Wardrobe-Room-Heater and Drying and Bleaching Apparatus;" and I do hereby declare that the following is a full, clear, and exact description of the same, reference being had to the accompanying drawings, making a part of this specification, in which—

Figure 1 is a perspective view; Fig. 2, a transverse section; and Figs. 3, 4, and 5, sections of the heating apparatus.

Similar letters of reference when they occur in the different figures represent corresponding parts of the invention.

This invention is designed as an improvement on my patent of September 4, 1866, for a dry-house, by which improvement a better control of the heat is obtained, and the invention may also be adapted to the different purposes indicated in the name.

To enable others skilled in the art to make and use my invention, I will proceed to describe it with reference to the drawings.

A, Fig. 1, represents the rectangular house or structure, with the doors thrown open, and a hinged section of the top F, forming a lid, raised. N represents the furnace, the mouth of which is shown in Fig. 1, with ash-pan, and a vertical slide for regulating the draft. D represents a triangular revolving heater, and b a shield or covering for the furnace N, heater D, and a horizontal section of pipe or chimney K, and is secured to the floor of the structure by nails, or any suitable means. d represents a hinged section of the shield, forming a door for access to the heater, and also for regulating the amount of heat escaping from the heater D into the structure. The shield b is also provided with tongued apertures n n n, for the admission of heat into the structure when the door D is closed.

C, Fig. 1, represents a horizontal sliding panel, forming a vapor-chamber in the top of the structure, of which the panel C is the bottom.

H is a pipe connecting between the structure above panel C and the chimney K. r r is a valve for opening and closing pipe H.

The relation of the furnace N, revolving triangular heater D, and chimney K, is shown in Figs. 3, 4, and 5. The tubes i, Fig. 3, and j, Fig. 4, serve as axles for the revolving heater, and also allow communication between the furnace N, through the hollow heater D and the chimney K, the aperture f working on tube i and tube j in aperture h.

D, Fig. 2, represents an end view of the triangular revolving heater; the lines p p p its motion; q q q q are outlines of the furnace, and b of the shield. The bottom of the structure is closed, excepting underneath the shield D, admitting only what air passes up through the shield. t t t are bearings secured in each end of the structure to support bars for holding fruit-drawers, clothing, bonnets, &c.

The revolving triangular heater insures a better control of the heat than is obtained in any other way, the heat being radiated more forcibly in direct lines from either of the sides, and, from its tendency to rise, the heat may be thrown upward or to one side, according to the position of the highest side of the heater.

The retention of the heat in the structure is regulated by the valve r r, and the current of ascending heat may be diverted from one end of the structure to the other by means of the sliding panel C, which panel, being shorter than the structure, when it is slid to one end forces the current to the other in order to escape through the pipe H. The heat may also be permitted to escape suddenly by raising lid F. As a room-warming apparatus, the front doors are thrown open, and the heater turned with one side to the front, at an angle of forty-five degrees, with one of the sides upward.

The heater is also a convenient arrangement for heating smoothing-irons, and by laying thin strips of metal or other suitable material on the heater, to sprinkle the sulphur on, the apparatus is complete for bonnet-bleaching.

Having thus fully described my invention, what I claim, and desire to secure by Letters Patent, is—

1. The revolving triangular heater D, arranged as and for the purposes set forth.

2. The shield *b*, when provided with apertures, and arranged substantially in the manner and for the purposes specified.

3. The combination of the furnace *N*, when provided with tube *i*, or its equivalent, the revolving triangular heater *D*, when provided with tube *j*, or its equivalent, and the chimney *K*.

4. The sliding panel *C*, substantially in the manner and for the purpose described.

JOHN K. BOSWELL.
